US0D1052184S

(12) United States Design Patent (10) Patent No.: US D1,052,184 S
(45) Date of Patent: * Nov. 19, 2024

(54) ACCESSORY FOR NAIL POLISHER

(71) Applicant: SHANGHAI WELL-SUN PRECISION TOOL CO., LTD.,
Shanghai (CN)

(72) Inventors: Mengyi Wang, Shanghai (CN); Jishun Wang, Shanghai (CN); Jing Sun, Shanghai (CN); Ren Liu, Shanghai (CN)

() Term: 15 Years

(21) Appl. No.: 35/519,915

(22) Filed: Dec. 13, 2023

(80) Hague Agreement Data

Int. Filing Date: Dec. 13, 2023

Int. Reg. No.: DM/234669

Int. Reg. Date: Dec. 13, 2023

Int. Reg. Pub. Date: Feb. 2, 2024

(30) Foreign Application Priority Data

Sep. 18, 2023 (CN) 202330607249.9
